CLAIM

The ornamental design for a sandal as shown and described.

DESCRIPTION

FIG. 1 is a bottom view of a sandal showing my new design; FIG. 2 is a top view thereof; FIG. 3 is a left side view thereof; FIG. 4 is a back view thereof; FIG. 5 is a right side view thereof; FIG. 6 is a perspective view thereof; and, FIG. 7 is a front view thereof.

The smaller evenly spaced lines on the sandal upper depict stitching, which forms no part of the claimed design. The broken lines showing the sole of the sandal form no part of the claimed design.
